UNITED STATES PATENT OFFICE

155,088

DESIGN FOR A SWITCH PLATE

Julius S. Johnson, Richland, Wash.

Application June 16, 1947, Serial No. 139,707

Term of patent 3½ years

(Cl. D26—13)

To all whom it may concern:

Be it known that I, Julius S. Johnson, a citizen of the United States, residing at Richland county of Benton, State of Washington, have invented a new, original, and ornamental Design for a Switch Plate, of which the following is a specification, reference being had to the accompanying drawing, forming a part thereof, wherein

Figure 1 is a face view of the switch plate, showing my new design, and

Figure 2 is an edge view of the switch plate.

I claim:

The ornamental design for a switch plate, substantially as shown.

JULIUS S. JOHNSON.
